DESIGN FOR A CHILD'S SCOOTER

Richard H. Arbib, Huntington Woods, Mich., assignor to United States Rubber Company, New York, N. Y., a corporation of New Jersey

Application August 16, 1947, Serial No. 140,920

Term of patent 14 years

(Cl. D34—15)

To all whom it may concern:

Be it known that I, Richard H. Arbib, a citizen of the United States of America, residing in Huntington Woods, county of Oakland, and State of Michigan, have invented a new, original, and ornamental Design for a Child's Scooter, of which the following is a specification, reference being had to the accompanying drawing, forming part thereof, wherein:

Fig. 1 is a perspective view showing the front and one side of the scooter; and

Fig. 2 is a perspective view showing this same side and the rear end of the scooter.

I claim:

The ornamental design for a child's scooter, as shown.

RICHARD H. ARBIB.
